UNITED STATES PATENT OFFICE.

EDWIN B. STIMPSON, OF BROOKLYN, NEW YORK.

DESIGN FOR A BEVEL-CUTTER.

SPECIFICATION forming part of Design No. 34,566, dated May 28, 1901.

Application filed March 29, 1901. Serial No. 53,561. Term of patent 7 years.

To all whom it may concern:

Be it known that I, EDWIN B. STIMPSON, a citizen of the United States, residing in the borough of Brooklyn, in the county of Kings and city and State of New York, have invented and produced a new, useful, and original design for an article of manufacture—namely, for a bevel-cutter for shaping and beveling the edges of articles made from sheet material, as leather, paper, and the like—of which the following is a specification.

In the accompanying drawings, which illustrate my design, Figure 1 is a plan of the cutter viewed in the direction indicated by the arrow *z* in Fig. 2, and Fig. 2 is an end view of the cutter as seen from the left in Fig. 1.

A designates the cutter as a whole, and *a* its cutting-face, which is shown in Fig. 2 as resting on a plane surface *x*. This face is in a plane which includes the entire cutting edge, and this edge has the general contour, when seen in plan, of two curves *y* from the respective extremities *b b* to the apex *c*, which is at the center of the cutter and projects out beyond the extremities *b b*. The curves *y* are shown as made up of short serrations.

The cutter has, Fig. 2, a rear beveled contour at *d* and a front beveled contour at *e*, these beveled planes or faces meeting at the cutting edge and are both oblique to the cutting-face *a*.

The two leading features of my design are the rear and front beveled contours *d* and *e*, both in planes oblique to each other and to the plane of the face *a*, in which the entire cutting edge lies, and also the said cutting edge being, when seen in plan, formed of two general curves *y*, extending from the common point *c* to the respective points *b*.

What I claim is—

The design for a bevel-cutter substantially as herein shown and described.

In witness whereof I have hereunto signed my name, this 26th day of March, 1901, in the presence of two subscribing witnesses.

EDWIN B. STIMPSON.
